SEARCHED
UNITED STATES PATENT OFFICE.

JOSIAH R. MCCOY, OF MARSHALLTOWN, IOWA.

HATCHET.

No. 901,022.

Specification of Letters Patent.

Patented Oct. 13, 1908.

Application filed January 14, 1907. Serial No. 352,318.

To all whom it may concern:

Be it known that I, JOSIAH R. McCoy, a citizen of the United States, residing at Marshalltown, in the county of Marshall and State of Iowa, have invented certain new and useful Improvements in Hatchets; and I do declare the following to be a full, clear, and exact description of the invention, such as will enable others skilled in the art to which it appertains to make and use the same.

The present invention relates to improvements in hatchets and aims to provide a novel implement of this character provided with a detachable bit and also with a removable cap applied to the poll and coöperating therewith to form a nail puller, the said bit and cap being adapted to be replaced when necessary.

The invention further contemplates a hatchet in which the frame thereof is formed entirely of sheet material, thereby enabling the same to be cheaply and economically manufactured.

For a full description of the invention and the merits thereof and also to acquire a knowledge of the details of construction and the means for effecting the result, reference is to be had to the following description and accompanying drawings, in which:

Figure 1 is a side elevation of a hatchet showing one embodiment of the invention. Fig. 2 is an end view of the same. Fig. 3 is a view similar to Fig. 1 showing a modification of the invention. Fig. 4 is an end view of the form shown in Fig. 3. Fig. 5 is a similar view showing a further modification. Fig. 6 is a side elevation of the form of invention shown in Fig. 5. Fig. 7 is a plan view of a lathers bit adapted to be employed with the construction shown in Figs. 1 and 2. Fig. 8 is a detail view of the bit employed in connection with the modification shown in Figs. 5 and 6.

Corresponding and like parts are referred to in the following description and indicated in all the views of the drawings by the same reference characters.

In the embodiment of the invention shown in Figs. 1 and 2 the frame or body portion of the hatchet is formed from a single piece of sheet material which is doubled upon itself at an intermediate point to form a loop F, the sides A—A of the loop being spaced from and parallel to each other and being connected at one end by the poll C.

At the opposite end of the loop the sides A—A are provided with the extensions 1—1, one of the said extensions being provided at the base of the loop with an offset portion 10 whereby it is thrown inwardly toward the opposite extension. Fitting within one end of the loop F and abutting against the poll C is a filler 11 which is provided with a recess facing the poll and communicating with a notch 12 formed in one end thereof. In the present instance this filler 11 is formed of sheet material and is of approximately U shape, the limbs thereof abutting against the poll and the said filler bearing against the upper side of the helve 13 which is inserted within the loop. Applied to the poll C is a removable cap 3 which is provided at its sides with the flanges E embracing the frame of the hatchet and secured thereto by means of the rivets 5 or fastening members which also engage the filler 11 to hold the same in position. If desired this cap 3 may be enlarged laterally so as to project beyond the sides of the frame and provide an increased striking surface for driving nails or like members. One end of this cap 3 is cut away at 14, the said cut away portion being in the form of a notch which is decreased in width toward the outer face of the cap and fits over the notch 12 in the poll and coöperates therewith to form a nail puller. Located at the opposite end of the loop F is an angle piece G one of the arms of which fits over the offset portion 10 and engages the lower side of the helve 13 while the opposite arm is disposed between the extensions 1—1 and is engaged by fastening members such as the rivets 15 passing through the same. The blade or bit B is held removably between the extensions 1—1 and is preferably formed with a plurality of cutting edges any selected one of which can be held in an operative position. As shown in Figs. 1 and 2 of the drawing the bit B is rectangular in shape and is formed with four cutting edges, the central portion of the bit having four openings therein any selected three of which may be engaged by the three screws O passing through the extensions to hold the desired cutting edge in operative position. In Fig. 7 is shown a lathers bit B' which can be substituted when desired for the square edged bit B.

A slightly different embodiment of the in-

vention is shown in Figs. 3 and 4 in which the bit B' is formed integral with the frame. As shown in these two figures the extensions 1^a at the lower end of the loop F fit closely together and are held rigidly in this position by the rivets 5^a. It will be observed that one of the extensions 1^a projects beyond the opposite extension and has the extremity thereof enlarged laterally and sharpened to 10 form the bit B', the said bit being of the type employed by lathers and embodying two rounding cutting edges N. The upper portion of the hatchet in these figures is practically identical with that previously 15 described in connection with Figs. 1 and 2.

A still further modification is shown in Figs. 5 and 6 in which the frame 16 of the hatchet is molded or otherwise formed from a solid piece of material, being formed with 20 the usual loop or eye F or for receiving the helve. The poll portion of the frame 16 is enlarged and formed at one end with a recess or notch H corresponding to the notch 12 of Figs. 1 and 2. Fitting removably over 25 the poll C' is a cap 3^a provided with side flanges embracing the frame and held in position by the fastening members or rivets 5^b. One end of this cap is notched at 14^b the 30 said notch gradually decreasing in width toward the outer face of the cap and fitting over and coöperating with the notch H so as to form a nail puller. The lower end of the frame 16 is reduced in thickness and bifurcated as indicated at R, the bit B² being 35 removably clamped between the arms of the bifurcation by means of the screws O'. A detail view of this bit B² is shown in Fig. 8 and it will be observed that the same is provided with a pair of openings and with a 40 notch in the upper edge thereof, the two openings being designed to receive two of the screws O' and the notch to receive the third screw O'. With a hatchet constructed in accordance with this invention it will be 45 readily apparent that the two parts which are subject to the greatest wear, namely the bit and the cap fitting over the poll can be readily removed and replaced as desired, thereby greatly prolonging the life of the 50 tool. Attention is also directed to the fact that the sheet metal blank from which the hatchet shown in Figs. 1 and 2 is formed is rectangular in shape and formed with

straight edges, thereby eliminating waste when the blanks are formed.

Having thus described the invention, what is claimed as new is:

1. A tool of the character described having the body portion thereof formed of a piece of sheet material which is looped upon itself, the poll of the body portion being provided with a recess, and a detachable cap applied to the said recessed poll of the body portion and coöperating therewith to form a nail puller.

2. A hatchet having the poll thereof recessed, and a cap applied to the poll and provided with side flanges embracing the same, the said cap coöperating with the recessed portion of the poll to form a nail puller.

3. A hatchet having the frame thereof formed with a loop, one end of the loop being notched, and a cap applied to the notched end of the loop and coöperating therewith to form a nail puller.

4. A hatchet having the frame thereof formed with a loop, one end of the loop being notched, a recessed filler fitting within the notched end of the loop, and a cap applied to the said notched end of the loop and coöperating therewith and with the recessed filler to form a nail puller.

5. A hatchet having the frame thereof formed with a loop and one end of the loop being notched, a U-shaped filler fitting within the notched end of the loop, and a cap applied to the notched end of the loop and coöperating therewith and with the U-shaped filler to form a nail puller.

6. A hatchet having the frame thereof formed of a blank of sheet material which is looped upon itself, one end of the loop being notched while the opposite end is provided with extensions, a bit clamped between the extensions, and a cap applied to the notched end of the loop and coöperating therewith to form a nail puller.

In testimony whereof I have hereunto set my hand in presence of two subscribing witnesses.

JOSIAH R. McCOY.
